UNITED STATES PATENT OFFICE

96,670

DESIGN FOR A SHEET DISPENSER PANEL

Paul H. Horwitt, Hartsdale, N. Y., assignor to Marathon Paper Mills Company, Rothschild,
Wis., a corporation of Wisconsin

Application March 11, 1935, Serial No. 55,827

Term of patent 3½ years

To all whom it may concern:

Be it known that I, Paul H. Horwitt, a citizen of the United States, residing at Hartsdale, in the county of Westchester and State of New York, have invented a new, original, and ornamental Design for a Sheet Dispenser Panel, of which the following is a specification, reference being had to the accompanying drawing, forming a part thereof.

Fig. 2 is a sectional view taken on line 2—2 of Fig. 1.

I claim:

The ornamental design for a sheet dispenser panel, as shown.

PAUL H. HORWITT.
